UNITED STATES PATENT OFFICE

KENT A. HAWLEY, OF BALTIMORE, MARYLAND, ASSIGNOR TO LOCKE INSULATOR CORPORATION, OF BALTIMORE, MARYLAND, A CORPORATION OF MARYLAND

INSULATOR WITH CAPS

Application filed March 1, 1930. Serial No. 432,490.

The invention relates to insulators and has special reference to the metal cap used in those of various types such as the post, pillar and pedestal.

It is well known that many types of insulators are provided at the top with metal caps having holes therein for the attachment of clamps, switch elements, bus bars and the like thereto. It is usually customary to form these caps of malleable castings and as tapped holes are provided for the reception of the screws used for attaching accessories to the insulator, fairly heavy bosses are provided at the holes. These large and heavy bolt bosses always contain soft spots in the middle and generally shrink cracks around the edges. Furthermore it is customary to drill the holes part way through the cap as otherwise if a bolt or screw of excessive length were used it would contact the porcelain and probably force the cap off. As a consequence the heavy bosses are of considerably greater depth than the holes therein, often actually one-fourth inch to three-eighths inches thicker than the effective length of the threaded hole. Another disadvantage is that considerable care must be exercised in tapping the holes especially as different tools are necessary to make the thread proper throughout the length of the hole.

It is with all of the above facts in view that I have devised the present invention which has for its principal object the provision of an insulator cap wherein the thickness of the bosses may be greatly reduced so that the overall height of the insulator will be decreased, without sacrificing any of its insulating value and so that cantilever strains will be diminished.

An important object of the invention is to provide an insulator cap which may be made of forged steel and in which the tapped holes for the reception of screws or bolts may be formed clear through the cap and subsequently closed or covered by special means.

An additional object of the invention is to provide a cap construction possessing these advantageous characteristics and which will at the same time be simple and inexpensive

to make, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a fragmentary view of a pedestal insulator equipped with my improved cap, the cap being partly broken away and in section, and

Figure 2 is a plan view of the cap with a portion thereof broken away and in section.

Referring more particularly to the drawings, it will be observed that I have disclosed a portion of an insulator 10 of the pedestal type in which the porcelain body is usually provided throughout at least the major portion of its length with ribs or corrugations 11 and provided at its upper end with a reduced tapered extension 12 upon which is mounted the cap 13. In the carrying out of my invention this cap is preferably formed as a steel forging and is of the usual general design in so far as shape is concerned, the size necessarily depending upon the particular insulator. At spaced points the top wall 14 of the cap is thickened at its juncture with the side wall 15, as shown at 16, and through these thickened portions holes 17 are drilled, these holes extending clear through and being tapped. Unless care be taken to use bolts 18 of the correct length when attaching accessories to the insulator, it is conceivable that the bolts might engage upon the top of the insulator body and force the cap off. As was mentioned above, this is prevented in the ordinary construction by stopping the holes internally of the thickened portions but as I do not elect to follow this plan I have devised other means for the purpose comprising the employment of an obstructing element covering the lower end of the hole and secured to the underside of the thickened portion at the hole. This might conceivably be a small disk or plate for each hole but I prefer to make use of a simple metal ring 19, which may be of comparatively thin steel, located within the

100

cap, lying against the underside of all of the thickened portions and positively secured thereto, for instance by welding. Such a ring requires only one operation for its securing whereas individual hole closure means would require four operations and consequently additional labor in assembling the parts. This ring constitutes adequate means for preventing the screws 18 from being inserted too far 5 and also serves as means to prevent access of water or moisture to the interior of the cap.

The cap having been formed in this manner is placed upon the reduced end 12 of the insulator body and secured thereon by the usual 10 cement mass 20.

The insulator equipped with the improved cap is of course used in the same manner as any other of the same type but possesses the advantage that the actual height of the thickened portions 16 is reduced as compared with the height of such in cap constructions where there are bottomed holes for the screws. The overall height of the insulator is consequently reduced, the thickness of the central portion 20 of the mass of cement 20 is decreased, and the cantilever strains on the porcelain diminished. The appearance of the insulator is of course improved but the principal advantage is the added durability and efficiency as the 25 shortening of the overall height does not in any way detract from the electrical efficiency, the leakage path being of the same length as if the insulator had not been shortened. It is believed that the construction, operation 30 and advantages will be apparent to one skilled in the art without further explanation.

While I have shown and described the preferred embodiment of the invention, it should be understood that the disclosure is merely 40 an exemplification of the principles involved as the right is reserved to make all such changes in the details of construction as will widen the field of utility and increase the adaptability of the device provided such 45 changes constitute no departure from the spirit of the invention or the scope of the claims hereunto appended.

Having thus described the invention, I claim:

50 1. In an insulator, a dielectric body, a metal cap secured upon the end of the body, said cap having its top wall provided with holes extending clear through, and imperforate metallic closure means united to the underside 55 of the top wall of the cap for covering said holes.

60 2. In an insulator, a dielectric body and a cap secured up one end thereof, the cap being provided on the inner side of its end wall with thickened portions merging into the side, said thickened portions being formed 65 with tapped holes extending entirely therethrough, and metallic plate means secured to the underside of said thickened portions for covering said holes.

3. In an insulator, a dielectric body and a metallic cap secured upon the upper end thereof, said cap being provided with a plurality of threaded holes extending clear through its top, and an annular imperforate 70 metallic plate means lying against the underside of the top wall for closing all of said holes.

4. In an insulator, a dielectric body and a metallic cap secured upon the upper end 75 thereof, said cap being provided with a plurality of threaded holes extending clear through its top, and metallic plate means secured on the underside of the top wall for closing said holes, said means being formed 80 as a ring.

5. In an insulator, a dielectric body and a metallic cap secured upon the upper end thereof, said cap being provided with a plurality of threaded holes extending clear 85 through its top, and metallic plate means secured on the underside of the top wall for closing said holes, said means being formed as a ring welded in place.

6. In an insulator, a dielectric body, a metallic cap secured upon the upper end thereof, said cap being provided with a plurality of holes extending clear through its top, and a metallic ring united to the underside of the top wall of the cap for closing said holes. 90

In testimony whereof I affix my signature.
KENT A. HAWLEY.
